UNITED STATES PATENT OFFICE.

JOHN DANIAL, OF SYRACUSE, NEW YORK.

TIME-CONTROLLED SWITCH.

Application filed November 17, 1925. Serial No. 69,601.

This invention relates to a time-controlled circuit breaker for electrically operated mechanism such as washing machines, centrifugal driers, baking and cooking utensils, electric heaters and any other devices to which the invention may be applied.

Many of these implements are adapted to be operated for relatively short but variable periods of time and the main object 10 of the present invention is to provide a practical and efficient circuit controller which may be easily and quickly set at will for any period of time to hold the electric circuit closed and it will automatically break 15 the circuit at the end of such interval although it is evident that practically the same device may be used for closing an open circuit by simply reversing the terminals of the time-operated switch.

20 Other objects and uses relating to specific parts of the device will be brought out in the following description.

In the drawings:

Figure 1 is a top plan of a time-controlled 25 electric switch embodying the various features of my invention.

Figure 2 is a sectional view taken on line 2-2, Figure 1, the lower portion of the clock case being broken away.

30 Figure 3 is a horizontal sectional view taken in the plane of line 3-3, Figure 2.

Figures 4 and 5 are detail sectional views taken in the planes of lines 4-4 and 5-5 respectively, Figure 3.

35 This device is adapted to be used as an attachment to a clock or other chronometer having a case extension —1— for receiving the various parts of the circuit controller, said case being provided with a cover plate

40 —2— having a sight opening —3— which is normally closed by a transparent plate —4—.

The circuit-controller forming the subject matter of this invention is adapted to 45 be installed in and upon the case —1— and comprises a clock actuated spindle —5— which, in this instance, may be the minute spindle of the clock and carries upon its upper end a dial wheel —6— having a circular dial —7— provided with a circular row of graduations numbered, in this instance, from zero to sixty concentric with the axis of the spindle and indicating fractions of an hour or minutes.

55 The wheel —6— is provided with an upturned marginal flange —8— projecting

above the upper surface of the dial —7— and adapted to be engaged by one end of a latch-lever —9— which is pivoted at 60 —10— to the inner end of a hand-operated slide or plunger —11—.

The plunger —11— is reciprocally movable in guides —12— on a supporting plate or frame —13— which is rigidly mounted within and upon the case —1—.

65 The other end of the slide —11— extends through an opening in one side of the case —1— and is provided with a handle —11'— by which it may be reciprocated.

The inner end of the latch lever —9— is 70 hook-shaped and, when the plunger —11— is forced inwardly, is adapted to ride over the upper edge and to engage the inner face of the adjacent portion of the flange —8— of the wheel —6— for temporarily holding 75 the plunger against outward movement until the latch is released in a manner presently described.

For this latter purpose, the flange —8— of the wheel —6— is provided with a radial 80 notch or slot —14— of just sufficient circumferential length to permit the inner end of the latch-lever —9— to pass easily therethrough when the slot —14— is registered with the latch.

85 A switch lever —15— is pivoted at —16— to the frame —13— and has one end projecting into the path of a shoulder —17— on the slide —11— and its other end movable into and out of engagement with a 90 pair of normally spaced switch terminals —18— which are also secured to the frame and are connected in an electric circuit —19— of a motor or other translating device to be controlled.

95 The switch blade —15— is adapted to be opened by a retracting spring —20—, Figures 3 and 4, which also serves to retract the slide or plunger —11— when released from engagement with the flange —8— of 100 the time wheel —6—.

The latch-end of the lever —9— is adapted to be pressed into holding engagement with the flange —8— of the wheel —6— by a spring —21— while the other end is engaged by an operating member —22— by which the latch may be tripped at will if desired.

105 As shown in Figure 5 the terminals —18— are insulated from each other and 110 from the frame —13— by bushings —23— of insulating material.

5 The time wheel —6— may be frictionally or otherwise secured to the minute spindle —5— to rotate therewith or the minute spindle —5— of the clock may as usual be frictionally connected to its driving mechanism to permit the time wheel —6— to be turned in either direction by hand without interfering with its frictional rotation by said spindle.

10

Operation.

Assuming now that the time wheel —6— is operatively connected to a clock or other chronometer and that it is desired to keep 15 the circuit —19— closed for a predetermined interval of time of, say fifteen minutes from a definite time of beginning then the time wheel —6— will be set by adjusting it rotarily by hand to register the predetermined interval of time required, in this instance, fifteen minutes of the time wheel 20 with a fixed index as —a— on the transparent plate —4— or other fixed part of the casing or with the latch end of the slide 25 —11— which is then pushed inwardly thereby causing the latch to ride over the upper edge of the adjacent portion of the flange —8— until its shoulder engages the inner face of said flange through the action of the 30 spring —21— thereby holding the slide —11— in its innermost position.

This inward movement of the slide —11— closes the switch lever —15— into engagement with its terminals —18— thereby closing 35 the circuit —19— for operating a translating device such as a motor in said circuit, the motor being used to operate any mechanism such as a washing machine or any other mechanism which it may be desired to operate for a definite period of time as selected 40 by the adjustment of the time wheel —6—.

As soon as the slide —11— and switch member —15— have been operated in the 45 manner just previously described they will be held in their adjusted positions by engagement of the inner end of the latch lever —9— with the inner end of the flange —8— of the time wheel —6— against the action of the retracting spring —20— which is of 50 comparatively light tension just sufficient to return the slide —11— and switch lever —15— to their starting positions without producing excessive frictional resistance 55 against the rotation of the time wheel.

The parts having been set in the manner described the time wheel —6— will continue 60 to rotate in a clockwise direction indicated by arrow —x— in Figure 3 until the slot or notch —14— registers with the latch-end of the lever —9— at which time the spring —20— will return the slide —11— to its starting position and will also open the switch member —15— for breaking the circuit at the end of the interval of time to 65 which the time wheel —6— has been pre-

viously adjusted resulting in the breaking of the circuit to the motor or other translating device for stopping the mechanism which may have been operated by said motor or translating device.

70

It is evident from the foregoing description that the time wheel —6— may be set for any other fractional period of an hour or, if desired, the time wheel may be operated by some other part of the clock mechanism at a greater or less speed than the minute spindle in which case the numbers on the dial —7— might indicate fractional parts of any other unit of time without departing from the spirit of this invention 80 and, therefore, I do not wish to limit myself to the construction shown and described.

75

If necessary, the latch-lever —9— may be tripped at will at any interval of time by simply depressing the member —22— by 85 hand.

What I claim is:

1. In a circuit controller of the character described, a time-actuated flanged wheel having a slot through the flange, a self-retracting latch-lever operable at will into engagement with the flange of the wheel, said wheel being adjustable rotarily to set the slot to different position relatively to the latch, the time rotation of the wheel serving to register the slot with the latch and thereby to release and permit the return of said latch to its starting position and an electric switch closed by the movement of the latch into engagement with the wheel and opened by the release of said latch from engagement with said wheel, and manually operated means for tripping the latch at any period during the rotation of the wheel.

90

2. In a circuit controller of the character described, a clock-actuated wheel having a circular row of graduations concentric with its axis and indicating fractions of a unit of time, said wheel having an annular flange provided with a radial slot in one side, a self-retracting slide having a latch movable into engagement with the flange when the slide is moved in one direction for holding the slide against return movement, said wheel being adjustable rotarily at will independently of its clock-actuation to set the slot to different positions relatively to the latch, said slide being released by the registration of the slot with the latch as the wheel is rotated by the clock, an electric switch, and means operated by the movement of the slide in reverse directions for closing and opening the switch, and means operable at will for tripping the latch and permitting the return of the slide at any period of 100 movement of the time wheel.

100

In witness whereof I have hereunto set my hand this 6 day of November 1925.
